BRUSH

Robert N. Miller, Rosemont, and William H. Grindall, Narberth, Pa., assignors to The Pennsylvania Railroad Company, Philadelphia, Pa., a corporation of Pennsylvania

Application March 3, 1943, Serial No. 477,887

12 Claims.

(Cl. 15—183)

This invention relates to brushes and has reference more especially to rotary brushes intended for employment in connection with railway track cleaning apparatus, such as disclosed in copending applications Serial Numbers 477,885 and 477,886 filed by us concurrently herewith.

Amongst the aims of our invention are to render brushes, particularly those of the kind specifically referred to, more sturdy than heretofore for capacity to withstand hard usage in sweeping heavy and closely packed cinders and/or sand, etc. from the railway track beds; to increase the useful life of the bristles; and to enable quick replacement of the bristles when necessary by reason of breakage or wear, at a minimum cost for time and labor.

In connection with brushes having the above attributes, it is a further object of our invention to effect, without necessitating the aid of additional or separate means, deflection of the sweepings laterally of the direction of brush movement,—in the case of brushes for track cleaning purposes—inwardly from opposite ends of the same to keep the sweepings within the confines of the track bed and thereby insure their complete removal in the manner set forth in the pending applications, supra.

How the foregoing and other objects and advantages can be readily realized in practice will appear from the following detailed description of the attached drawings, wherein Fig. 1 is a fragmentary view in side elevation of a rotary brush conveniently embodying our invention.

Fig. 2 is a broken out axial section of the brush viewed as indicated by the angled arrows II—II in Fig. 1.

Fig. 3 is a fragmentary detail cross sectional view taken as indicated by the angled arrows III—III in Fig. 2.

Fig. 4 is a plan view of one of the removable bristle-carrying segments of the brush.

Fig. 5 is a broken out perspective view of the backing plate of one of the brush segments.

Fig. 6 is a fragmentary detail sectional view of one of the brush segments taken as indicated by the angled arrows VI—VI in Fig. 4 and drawn to a larger scale.

Fig. 7 is a fragmentary cross sectional view taken as indicated by the angled arrows VII—VII in Fig. 2 and showing the means by which the brush segments are removably secured to the core component of the brush.

Fig. 8 is a perspective view of one of the bristle elements of the brush; and

Fig. 9 is a view corresponding to Fig. 4 showing a modification.

In Figs. 1 and 2 of these drawings, we have illustrated our improved brush in a rotary form adapted for use more especially in railway track cleaning apparatus of the sort featured in the copending applications hereinbefore referred to. As shown, the brush consists of three sections, an inner or center section 1 for operation on the 10 portion of a railway track between the rails R, R, and two similar end or outer sections 2 for operation respectively on the side margins of the track bed beyond said rails. Except for slight differences in certain structural details to be particularly pointed out later and for being somewhat smaller as regards length, the outer sections 2, 2 of the brush are generally like the middle section 1. Thus each of the brush sections comprises a core drum 5 with laterally spaced weld-secured heads 6 and 7 having axial bosses 8 and 9 which are centrally bored to fit a hollow drive shaft 10, and a plurality of segmental bristle-carrying components 11 (Figs. 3 and 4) which are detachably secured to the said 20 drum as presently explained, for convenience of ready removal when bristle replacements become necessary by reason of breakage or wear. From Figs. 3—5 it will be observed that each segment 11 includes a backing plate 12, which, for the most part is perforated, and which is transversely concave to fit the drum 5, the perforations 13 being arranged in intersecting longitudinal and crosswise rows. Centrally of opposite ends each 25 backing plate 12 is provided on its outer face with square radially projecting lugs 15, and with holes 16 at opposite sides of said lugs, see Figs. 4 and 5. The brush bristles 17 are formed in pairs by bending cut lengths of flat strip material which may be of metal, into the form of elements 18, 30 such as the one illustrated in perspective in Fig. 8, having the configuration of a hairpin. Incident to assembling the segmental components of the brush sections in accordance with our invention, the ends 17 of the bristle elements 18 are thrust 35 outwardly through diagonally adjacent apertures 13 in the backing plate 12, the bristle elements in the group at the left of the transverse median of the plate in Fig. 4 being arranged at an angle contrary to that of the groups at the right. The 40 flats of the bristle ends 17 of the two groups are accordingly disposed at opposite inclinations to the direction of brush rotation (indicated by the arrows in Figs. 1 and 4), with the result that the sweepings are deflected inward of the ends of the 45 respective brush sections 1 and 2 to keep them 50 55

within the confines of the track bed. At the inner face of each backing plate 12, the apertures 13 are beveled as at 13a in Figs. 3 and 6 for substantial conformity with relatively sharp head roundings of the hairpin bristle elements 18. Suitably bonded or otherwise secured to the outer face of each backing plate 12 is a relatively thick layer 19 of elastic material such as rubber or the like which is penetrated by the bristle ends 17, and which serves to reinforce the latter adjacent their roots to prevent fatiguing and fracture of the metal of the bristles incident to the use of the brush. In order to facilitate placement of the brush segments 11, the drums 5 are provided at circumferential intervals with spacing ribs or ridges 20, see Figs. 2 and 3, which have end projections 20a engaging through the shell of the drum 5, and which are secured by welding. As instanced in Fig. 7, the segmental components 11 of the center brush section 1 are fastened to the drum 5 of that section by screw bolts 21 whereof the shanks pass through the holes 16 in the ends of the backing plates 12 of such segments and take into the peripheral flanges of the drum heads 6 and 7. In each of the outer brush sections 2, the backing plates 12 of the segmental components 11 are similarly secured by screw bolts 21 respectively to the head 6 at the inner end of such section, and to flanged rings 22 welded into the outer end of the drum 5. Due to the greater length of the center brush section 1, a split two-part clamp band 25 (Fig. 2) is employed as an additional securing means, said band embracing the backing plates 12 in central blank spaces 23 (Fig. 4) between the two bristle groups in said plates. At opposite ends, the brush sections 1 and 2 are provided with annular caps 26 which are of angular cross sectional configuration and fit over the series of radial projections 15 of the several backing plates 12, and which are secured to the heads 6 and 7 by bolts shown at 27, the peripheral flanges 26a of said caps bearing laterally against the endmost bristles 17. Each smaller brush section 2 is similarly provided with end caps 28, one of which is bolted to the inner head 6 of such section, while the other of said caps is bolted to the flange ring 22.

Clamped to the shaft 10 between the central and the outer brush sections 2 are collars 30 which have lateral clutching engagement as at 31 with the bosses 9 of the contiguous drum heads 6 and 7 of said sections. The drum heads 7 of the smaller brush sections 2 are disposed well inward of the outer ends of said sections and have lateral clutching engagement at 32 respectively with collars 33 secured to trunnion extensions 34 of the hollow shaft 10. As shown, the inner end portions 34a of the trunnions 34 fit into the ends of the shaft 10 and are secured to the latter by welding as at 35, the collars 33 being keyed to said extensions at 36. As a consequence of the construction just described, it will be seen that the brush sections 1 and 2 are fixed against independent rotation relative to their common carrier shaft 10.

In practice, the brush is intended to be supported, with capacity to rise and fall relative to the track bed, by a pair of arms 37 having pivot eyes 38 at their outer ends, see Fig. 1. As shown in Fig. 2, the arms 37 carry ball-bearings of which the housings are indicated at 39, in which bearings the shaft extensions 34 are freely journaled. One of the shaft extensions 34 (that at the left of Fig. 2) protrudes through the corresponding

bearing housing 39, see Fig. 2, for attachment thereto of a toothed wheel 40 adapted to be chain driven in the way disclosed in our copending applications hereinbefore identified.

In the modification of Fig. 3, the bristle elements 18a are arranged in overlapping relation, and their ends passed through diagonally opposite pairs of holes 13a in contiguous rows of the latter. This arrangement affords a greater number of bristle ends but does not result in lateral deflection of the sweepings as in the first described embodiment. In either embodiment, however, the angular disposal of the bristle flats with respect to the direction of brush movement, is advantageous in that the bristles are thereby stiffened against excessive flexure which ordinarily results in their taking a permanent bent or curved set with corresponding decrease in their sweeping efficiency.

Having thus described our invention, we claim:

1. A brush having a rigid foundation element; a perforated bristle anchorage member detachably secured to the foundation element; bristle elements of hairpin configuration with their ends passed through adjacent holes in the perforated anchorage member and their bristle connecting bights securely clamped between said element and said member; and a relatively thick layer of rubber bonded to the outer surface of the anchorage member and penetrated by the bristle ends for yieldingly bracing the latter adjacent their root anchorages.

2. A rotary brush having a foundation cylinder; and a plurality of bristle-carrying segments detachably secured circumferentially about the foundation cylinder, each such segment comprising a rigid transversely-arcuate plate which conforms to the curvature of the foundation cylinder, and which has a relatively thick layer of rubber or the like bonded to its outer face and penetrated by the bristles to yieldingly brace them at their roots.

3. A rotary brush according to claim 2, in which the bristles are of hair pin configuration with their ends passed through spaced apertures in the anchorage member, and with the bights connecting their ends clamped between said member and the foundation element.

4. A rotary brush according to claim 2, in which the bristles are formed from flat strip material to hair pin configuration with their ends passed through diagonally arranged pairs of apertures in the anchorage member, and with the bights connecting their ends clamped between said member and said foundation element.

5. A rotary brush having a rigid foundation cylinder; a series of coextensive circumferentially-spaced stop ridges projecting from and subdividing the outer surface of the cylinder in the segments; a plurality of bristle carrying elements removably secured to the cylinder, each such element comprising a rigid base plate of arcuate cross section coextensive in length with the cylinder and of a width to fit into the interval between a pair of stop ridges.

6. A rotary brush according to claim 5, in which cover caps removably secured to the opposite ends of the cylinder circumferentially overlap the ends of the plates of the several bristle-carrying segments.

7. A rotary brush according to claim 5, in which cover caps removably secured to the opposite ends of the cylinder circumferentially overlap the ends of the plates of the several bristle-carrying segments, and have projecting peripheral flanges to

laterally contact the endmost bristles of the several segments.

8. A rotary brush according to claim 5, in which headed bolts secure the plates adjacent their ends to the cylinder; in which the plates are provided adjacent their ends with outwardly projecting lugs somewhat higher than the heads of the securing bolts; and in which cover caps secured to the opposite ends of the cylinder fit circumferentially about the lugs on the plates and overreach the heads of the securing bolts.

9. A rotary brush according to claim 5, in which headed bolts secure the plates adjacent their ends to the cylinder; in which the plates are provided adjacent their ends with outwardly projecting lugs somewhat higher than the heads of the securing bolts; and in which cover caps secured to the opposite ends of the cylinder fit circumferentially about the lugs on the plates to overreach the heads of the securing bolts, and are formed with extended peripheral flanges to laterally contact the endmost bristles of the several segments.

10. A rotary brush according to claim 5, in which bolts are employed to secure the plates at their ends to the cylinder; and in which the plates are held to the cylinder intermediate their ends by an enveloping strap band.

5 11. A brush having a foundation element; and a bristle anchorage member detachably secured to the foundation element, said member being in the form of a rigid apertured plate, and the bristles being of hair pin configuration with the ends of pairs of them passed through diagonally arranged pairs of the plate apertures, and with the connecting bights of such bristle pairs crossed one over the other and clamped between said plate and the foundation element.

10 12. A rotary brush having a foundation cylinder; and a plurality of bristle-carrying segments detachably secured circumferentially about the foundation cylinder, each such segment being in the form of a rigid transversely-arcuate apertured plate which conforms to the curvature of the foundation cylinder, and the bristles being of hair pin configuration with the ends of pairs of them passed through diagonally arranged pairs of the plate apertures, and with the connecting bights of such bristle pairs crossed one over the other and clamped between said plate and the foundation cylinder.
